Patented July 12, 1887.

UNITED STATES PATENT OFFICE.

JOHN T. WEBSTER, OF FLUSHING, NEW YORK.

DESIGN FOR A CARPET.

SPECIFICATION forming part of Design No. 17,455, dated July 12, 1887.

Application filed June 15, 1887. Serial No. 241,438. Term of patent 3½ years.

To all whom it may concern:

Be it known that I, JOHN T. WEBSTER, a citizen of the United States, residing at Flushing, in the county of Queens and State of New York, have invented and produced a new and original Design for Carpets, of which the following is a specification, reference being had to the accompanying photographic illustrations.

10 The distinguishing features and characteristics of my design will be most clearly understood by reference to the accompanying phototographic representations thereof, which form a part of this specification.

I claim—

15 The design for carpets, substantially as shown and set forth.

In testimony whereof I affix my signature in presence of two witnesses.

JOHN T. WEBSTER.
